(57) **CLAIM**

The ornamental design for an electrophoresis cassette, as shown and described.

DESCRIPTION

FIG. 1 is a front perspective view of the electrophoresis cassette according to the design.

FIG. 2 is a front plan view of the electrophoresis cassette.

FIG. 3 is a left side view of the electrophoresis cassette.

FIG. 4 is a right side view of the electrophoresis cassette.

FIG. 5 is a bottom plan view of the electrophoresis cassette.

FIG. 6 is a top plan view of the electrophoresis cassette.

FIG. 7 is a back plan view of the electrophoresis cassette; and, FIG. 8 is a back perspective view of the electrophoresis cassette.
